UNITED STATES PATENT OFFICE.

ALBERT H. TAYLOR, OF EASTON, PENNSYLVANIA, ASSIGNOR TO INGERSOLL-RAND COMPANY, OF NEW YORK, N. Y., A CORPORATION OF NEW JERSEY.

HAMMER-DRILL.

971,223.

Specification of Letters Patent. Patented Sept. 27, 1910.

Application filed October 1, 1907. Serial No. 395,339.

To all whom it may concern:

Be it known that I, ALBERT H. TAYLOR, a citizen of the United States, and resident of Easton, in the county of Northampton 5 and State of Pennsylvania, have invented a new and useful Improvement in Hammer-Drills, of which the following is a specification.

My invention consists in certain improvements in that class of pneumatic tools known as hammer drills in which an air power feed is provided for forcing the tool forward and holding it in its working position.

15 The object of my invention is to provide a controlling valve in the head block of the drill, which valve is so constructed and arranged that it may be operated to control the admission of air to the hammer thus 20 rendering the tool easy to handle and to set up.

A further object is to provide a tool in which the valve is held onto its seat by spring pressure whereby the wear thereon 25 is taken up automatically.

My invention further consists in means for automatically locking the controlling valve in its different positions against any tendency to be displaced therefrom by the 30 jars incident to the operation of the tool.

A practical embodiment of my invention is represented in the accompanying drawings, in which—

Figure 1 represents a portion of an air feed hammer drill in side elevation partially in longitudinal central section with my invention applied thereto, the controlling valve being shown in its closed position, Fig. 2 is a detail section showing the relative location of the ports in the valve and the head block when the valve is closed, Fig. 3 is a detail section showing the positions of the ports in the valve and head block when the valve is open, and Fig. 4 is a detail plan 45 view of the locking plate carried by the valve.

The cylinder of the hammer drill is denoted by 1 and its head block by 2. In the form shown, the air feed cylinder 3 is directly attached to the head block 2.

The hollow air feed piston rod is denoted by 4 and its head by 5. The rod 4 extends rearwardly through the outer end 6 of the cylinder 3 and forms the rear support for 55 the tool. The space 7 back of the piston

head 5 is at all times open to external atmosphere through ports 8 in the outer end 6 of the cylinder.

The air supply pipe is denoted by 9 and it is attached to the piston rod 4 exterior 60 to the cylinder 3. This air supply pipe may be provided with a cock 10 for opening and closing the same.

The head block is provided with a hole therethrough having a taper portion forming a seat 15 for the tapered portion 16 of the controlling valve. This controlling valve is provided with a cylindrical extension 17 having an angular portion 18 for fixing thereon the locking plate 19 and the handle 70 20 exterior to the head block. All wear between the valve and its seat is taken up automatically by its spring 21 interposed between the larger end of the said valve and a cap 22 which has a screw threaded engagement with the hole through the head block 75 2 exterior to the taper portion which forms the seat 15.

The controlling valve is provided with a through port 23 and the head block is provided with ports 24, 25, leading respectively 80 from the valve seat to the air feed space 26 and the hammer feed space 27.

The locking plate 19 is provided with a shoulder 28 arranged to engage a stop 29 on 85 the head block 2 when the valve is closed to limit its movement in that direction. The locking plate is further provided with a shoulder 30 arranged to engage said stop 29 when the valve is open to limit the movement of the valve in that direction. The valve is locked against unintentional displacement in its open and closed positions by providing the locking plate with sockets 31, 32, arranged to alternately receive the 90 rounded end of a spring actuated pin 33 mounted in the head block 2.

In operation, supposing the parts to be in the position shown in Figs. 1 and 2, the cock 10 in the supply pipe is first opened to admit the air to the air feed space 26 within the cylinder and piston. This will cause the tool to be fed up to its work. The controlling valve is then opened thus opening the air feed to the hammer by bringing the 105 ports 23, 24, 25, into line. When it is desired to stop the operation of the tool, the controlling valve is closed. When it is desired to reset the tool, the cock 10 in the supply pipe is first closed. The controlling 110

valve is then opened to permit the air within the air feed space to escape through the hammer.

The construction herein set forth discloses 5 a very simple and effective means for controlling the supply of air to the tool and in the form shown a very rigid form of connection between the air feed cylinder and the tool is provided. Furthermore, the means 10 for locking the controlling valve against unintentional displacement obviates any danger of the valve becoming displaced by the jar incident to the operation of the tool.

While the invention has been described in 15 connection with an air power feed hammer drill any other fluid power may be utilized and any type of tool may be employed without departing from the spirit and scope of my invention.

What I claim is:—

In an air feed hammer drill, a head block, an air feed cylinder attached directly thereto, a hollow piston located in the said cylinder having its rod extended rearwardly to form a rear support for the drill, an air supply pipe leading to said hollow piston and a manually operated valve in the head block for controlling the communication between the air feed cylinder and hammer. 20 25

In testimony, that I claim the foregoing 30 as my invention, I have signed my name in presence of two witnesses, this 28th day of September, 1907.

ALBERT H. TAYLOR.
